Primary Examiner — Susan Moon Lee

(57) **CLAIM**

We claim the ornamental design for a scanner window assembly, as shown and described.

DESCRIPTION

FIG. 1 is a front perspective view of a scanner window assembly;

FIG. 2 is a bottom view thereof;

FIG. 3 is a side elevation view thereof;

FIG. 4 is a top plan view thereof;

FIG. 5 is a second side elevation view thereof, opposite to the side of FIG. 3;

FIG. 6 is a front elevation view thereof; and,

FIG. 7 is a rear elevation view thereof.
